AIR CIRCULATOR FOR ORCHARDS AND
FIELD CROPS

Leo B. Gaskill, Pomona, Calif.

Application September 2, 1950, Serial No. 183,031

3 Claims. (Cl. 170—160.57)

1

This invention relates to a device for the circulation of air, and which is particularly adapted for use in orchards, field crops, or the like, to prevent frost damage.

Traditionally, the heating of orchards, fields, or groves, wherein it is desired to protect tender trees and crops from freezing temperatures, has been accomplished by the use of individual "orchard heaters" utilizing the heating effect of the combustion of fuel oil, and the like. This system is often used for citrus groves. Such use of "orchard heaters" is disadvantageous, operation being cumbersome; and undesirable smudge is produced. Accordingly, some attempts have been made to supersede the use of such "orchard heaters" by the use of devices for the production of the circulation of air masses, it being well known that the circulation of air will elevate the atmospheric temperature.

It is one object of this invention to provide a novel and improved mechanism for the circulation of air designed to protect trees and crops from freezing temperatures.

In achieving an improved operation, use is made of a novel design of impeller blades whereby a pressure is imposed broadly upon the lower levels of air in order to prevent the rise of air that has been warmed during the day, rather than to create extreme turbulence that will dissipate this warmed air. Accordingly, the impeller blades are of substantial angular width, and are designed to extend generally at an angle to the axis of rotation, and to be rotated at relatively slow speeds.

It is another object of this invention to provide a device of this character that is substantially noiseless in operation. This object is achieved by providing a device that can be rotated at relatively low speeds and yet produce the desired results.

It is a further object of this invention to provide a device of this character that can be adjusted to control the flow pattern of air in order to meet the particular requirements of groves or orchards designed to be heated. Accordingly, novel means are provided for adjusting the angle of the impeller blades to the axis of rotation of the device according to the extent and topography of the grove or orchard designed to be heated.

It is still a further object of this invention to provide a device of this character that can be adjusted to control the velocity of air being circulated, and the pressure being imposed on the lower levels of air, all in accordance with the needs of the system.

It is still a further object of this invention to provide a device of this character that affects the surrounding air in a non-directional manner, maintaining continuous pressure and velocity

2

conditions on the surrounding air. For this purpose, the mechanism is designed to be rotated about a vertical axis.

It is still a further object of this invention to provide a device of this character that is simple in structure, but yet sturdy and efficient in operation.

It is still a further object of this invention to provide a device of this character that has novel provisions whereby the operative parts of the device can be readily reached for maintenance and repair, and that facilitates the installation of the device. For this purpose, means are provided whereby the entire apparatus may be moved to horizontal position.

This invention possesses many other advantages, and has other objects which may be made more clearly apparent from a consideration of several embodiments of the invention. For this purpose there are shown a few forms in the drawings accompanying and forming part of the present specification. These forms will now be described in detail, illustrating the general principles of the invention; but it is to be understood that this detailed description is not to be taken in a limiting sense, since the scope of the invention is best defined by the appended claims.

Referring to the drawings:

Figure 1 is a plan view of a device incorporating one form of this invention;

Fig. 2 is an elevation, with parts partly broken away, showing the entire apparatus;

Fig. 3 is a sectional view, taken along the plane indicated by line 3—3 of Fig. 2;

Fig. 4 is a view taken in the direction of the plane indicated by line 4—4 of Fig. 2, some of the blades being omitted;

Fig. 5 is an elevation, a portion of which is broken away to illustrate the manner in which the pitch of the blade may be selectively adjusted, and also partly in section along a plane corresponding to line 5—5 of Fig. 4 to illustrate the manner in which the upper supporting means for the tiltable mechanism may be selectively adjusted;

Fig. 6 is a sectional view, taken along the plane indicated by line 6—6 of Fig. 5, the view diagrammatically illustrating one of the adjustments of the mechanism;

Fig. 7 is a view, partly in section, illustrating a modified form of this invention;

Fig. 8 is a view, partly in section, taken in the direction indicated by arrows 8—8 of Fig. 7, some of the blades being omitted; and

Fig. 9 is a view of the driving apparatus, partly in section, taken in the direction of the arrows 9—9 of Fig. 7.

The surrounding mass of air is circulated for heating purposes by a plurality of impeller blades (in this instance, there are three). These

blades are mounted in such a manner that they are rotatable about a vertical axis A, so that they may set up a flow of air in the surrounding vicinity.

In the form illustrated in Figs. 1 to 6, inclusive, such mounting is provided by the support 11, a cylindrical housing 12 forming a mast mounted on the support 11, a support or hub member 13 joined to a rotary shaft 48, and mounted on the housing 12, as by the aid of an appropriate thrust bearing structure 14 (see Figs. 4 and 5), and a plurality of plates 15 secured to the hub 13 and substantially equiangularly spaced thereof. To each impeller blade 10 is secured a base or disc 16, respectively adapted to be adjustably supported on the plates 15 carried by the hub 13 in a manner to be hereinafter more fully described.

Each of the plates 15 is mounted on the hub 13 in such a manner that they may be adjusted to control the angle of each blade 10 with respect to the vertical axis A. The control of the angle of the blade 10 to the vertical will, in turn, control the flow pattern of the air. Thus, depending upon the angle which the blade 10 makes with the axis of rotation A, the air can be directed to reach a larger or smaller area of land, all depending upon the particular needs of the installation. Further, this adjustment can compensate for the particular topography of the land designed to be affected.

For this purpose of adjusting the angle of the blades 10 with respect to the axis of rotation A, each of the plates 15 is angularly adjustable about an axis displaced from the axis of rotation of the hub 13, and transverse thereto. Accordingly, the hub 13 carries near its periphery a plurality of pairs of ears 17 that may be welded, or otherwise secured, to the hub 13. Short shafts 18 are attached, at their ends, within the ears 17. Plates 15 carry brackets 19 through which the shafts pass. The shafts thus pivotally support the plates 15 on horizontal axes, adjacent the periphery of these plates.

For fixing the particular desired angle at which plates 15 are inclined, a central sleeve 20, secured to the hub 13, carries a plurality of brackets 21, respectively cooperating with the plates 15. Each bracket has a face 21a at a substantially constant distance from the axis of adjustment of the respective plate, as defined by ears 17 (Fig. 5). Each plate 15, at its inner face, carries a right-angle extension 22, adapted to cooperate with the bracket 21. The adjacent faces of each bracket 21 and cooperating extension 22 have clearance for permitting relative adjustment thereof. This extension 22 provides a through aperture 23. The bracket 21 has a plurality of apertures 24 adapted selectively to register with the aperture 23 of the extension 22. The extension 22 is adapted thereby to be pin-connected to the bracket 21, as by the aid of bolt assembly 25. Proper choice of an aperture 24 determines the angular position of plate 15.

Any suitable type of blade may be incorporated in the structure. In this instance, as shown most clearly in Figs. 1, 2, and 5, the blade 10 is formed of plane surfaces, there being a tip portion 26 that may be formed by bending the tip about an axis transverse to the axis of the blade, the axis of bending being preferably inclined to provide a leading edge for the blade 10, as shown most clearly in Fig. 1.

Each blade is provided with turned-up edges 28. A channel rib 29 forms the basic structural

support for the blade 10, and the rib 29 may be substantially centrally disposed thereof, and secured to the blade 10 as by the use of rivets, or by welding.

As shown most clearly in Figs. 4 and 5, the rib 29 is secured to the disc 16 near the periphery of the disc, as by welding, and an auxiliary brace 30 serves to add rigidity to the system by connecting the rib 29 to the plate 16 at a place on the disc 16 opposite the rib 29.

The disc 16 is adjustably attached to the adjustable plate 15, as by the aid of a bolt assembly 31, extending through substantially centrally disposed through apertures of the plate 15 and the disc 16, respectively. By this connection any angular adjustment of the plate 15 about the axis formed by the shaft 18 will be transmitted to the blade 10, and a rotation of the hub 13 will cause corresponding rotation of the blades 10.

The particular mounting of the blades 10, utilizing the plate 15 and disc 16, is such that, with comparative ease, provisions can be made to adjust the pitch of the blades 10 in order further to control the flow characteristics of air designed to be circulated. Thus, as shown most clearly in Figs. 4 and 6, one of the members coupled by the bolt assembly 31, in this instance, the plate 15, is provided with a plurality of through apertures 32 spaced at intervals along an arc of which the bolt assembly 31 forms the center. The other member, in this instance the disc 16, carries a removable pin 33 having a shank portion adapted to extend through any one of the apertures 32. To render possible such adjustment, the bolt assembly 31 is first loosened. To retain the pin 33 in place, suitable means, such as a key connection 34, may be used. The blade 10 being joined to the disc 16, Fig. 6 illustrates that, by appropriate positioning of the pin 33, the pitch of the blade 10 can be varied.

As shown most clearly in Figs. 1 and 2, the blades 10 may be supported in the desired position by the use of support members 35, extending respectively between each adjacent blade 10, and suitably adjustably secured thereto. Also provided are the support members 36, extending from the blades 10 to a central ring 37 and designed to resist the forces acting on blades 10 due to their rotation.

The support 11 for the device is mounted on a base 38 in a manner permissive of rotation about a horizontal axis in order that the mechanism may be reached for repair or adjustment, and also to facilitate the original installation of the device. For this purpose, as shown most clearly in Figs. 2 and 3, the base 38 and support 11 are hinged together. The base 38 carries a beam 39 which, in turn, carries a horizontal shaft 40 by the aid of brackets 41. Appropriate brackets 42, cooperable with the shaft 40, are secured to the base 11, as by the aid of bolt assemblies 43. For securing the support 11 in horizontal position, the base 38 also carries a beam 44 with which bolt assemblies 45 may cooperate.

In the vertical position of the mechanism, suitable guy wires 46, or the like, may be attached to the housing 12 by the aid of a collar 47.

For imparting rotation to the hub 13 and the blades 10, the shaft 48, appropriately coupled to the hub 13 and extending through the housing 12, is adapted to be rotated by a driving mechanism including, in this instance, a motor 49 mounted on the base 38 (see Figs. 2 and 3). Interposed between the housing 12 and the support

11 is a gear housing 50 accommodating a pair of intermeshing bevel gears 51 and 52, the gear 52 being secured to the shaft 48. The bevel gear 51 is suitably supported in the gear housing 50, and secured to the gear 51 is a drive shaft 53 extending through the housing 50. The shaft 53 carries a sprocket wheel 54 adapted to cooperate with a continuous chain 55. For moving the chain 55, the motor 49 also carries a sprocket wheel 56 cooperable with the chain 55. The use of the chain drive mechanism permits ready disassembly of the motor 49 from the remainder of the drive mechanism so that, when desired, the support 11 carrying the mechanism can be rotated about the hinge 48, 42.

In the form of the invention illustrated in Figs. 7, 8, and 9, the blade assembly 10 is illustrated as substantially identical to the form shown in the form of Figs. 1 to 6. However, in the present instance, the supporting structure for the blade 10 is simplified.

A blade support 60, generally of hollow, frustoconical shape, provides a plurality of substantially plane faces 61 substantially equiangularly disposed about the support 60. These faces 61 cooperate respectively with the blade discs 16 in a manner not dissimilar from the manner in which the plates 15 of the form of Figs. 1 to 6 cooperate therewith, for the purpose of permitting ready adjustment of the pitch of the blades 10 to control the flow characteristics of the air designed to be circulated.

Substantially centrally of each face 61, as seen most clearly in Fig. 8, there is provided an aperture 62 with which a bolt assembly 63 cooperates to secure the blade disc 16 thereto. Any one of a number of arcuately spaced apertures 64 cooperates with the removable pin 33 of the blade disc 16, whereby the pitch of the blade 10 is capable of adjustment.

The support 60 is mounted for rotation with a hollow drive shaft 65. The support 60 rests on a shaft casing 66 for relative rotation with respect thereto. For this purpose, a roller bearing support is provided. One race 67 is carried by the end of the casing 66, and another race 68 is carried interiorly of the support 60 by means of an annular flange 69 and a shoulder 70 thereof. Disposed between the race members 67 and 68 are suitable rolling elements 71.

Forming a driving connection between the shaft 65 and the support 60 are a pair of semi-circular coupling elements 72, each having depending lugs 73 cooperable with corresponding slots 74 in a driving extension 75 of the upper base 76 of the support 60. The coupling elements 72 are clamped to the shaft 65 by means of bolt assemblies 77 passing through opposed ears 78 of the elements 72.

The shaft 65 may be rotated by suitable means, such as is illustrated in connection with the forms shown in Figs. 1 to 6.

While the angle of the support for the blades 10 is not capable of adjustment in the construction illustrated, the support member 60 has faces 61 inclined at the particular angle that the installation requires. Different support members 60 can, of course, be used in this construction. The construction promotes interchangeability of supports 60, assembly of the apparatus being easily accomplished.

The inventor claims:

1. In apparatus of the character described: a hub rotary about a first axis; means supported

by the hub providing a second axis spaced from the first axis and in a direction at a right angle to a plane including the first axis; a plate pivoted on said means about said second axis for tilting movement of said plate; adjustable means interconnecting the hub and the plate for maintaining said plate in any of a number of angular positions about said second axis; and a blade structure having a base; said plate having means providing a third axis about which the blade base is angularly adjustable, said third axis and the first axis lying in a plane normal to the second axis.

2. In a device of the character described: a hub rotary about a first axis; a plate having a surface; means mounting said plate on said hub for tilting movement of said surface about a second axis normal to one plane including said first axis, said second axis being spaced from said first axis; adjustable means interconnecting the hub and the plate remote from said second axis for maintaining said plate in any of a number of angular positions about said second axis; a blade structure having a base, said base having a surface substantially normal to the longitudinal axis of the blade and in engagement with said surface of said plate; said plate having means providing a third axis normal to surfaces about which said blade base is angularly adjustable; means interconnecting said plate and base remote from said third axis for maintaining said base in any one of a number of angular positions about said third axis with respect to said plate; said third axis lying in said one plane.

3. In a device of the character described: a hub rotary about a first axis; a plate having a surface; means mounting said plate on said hub for tilting movement of said surface about a second axis normal to one plane including said first axis, said second axis being spaced from said first axis; means remote from said second axis for maintaining said plate in any of a number of angular positions about said second axis including an adjustable removable connection between said plate and said hub; a blade structure having a base, said base having a surface substantially normal to the longitudinal axis of the blade and in engagement with said surface of said plate; said plate having means providing a third axis normal to surfaces about which said blade base is angularly adjustable; means remote from said third axis for maintaining said base in any one of a number of angular positions about said third axis with respect to said plate including a removable connection between said base and said plate; said third axis lying in said one plane.
